UNITED STATES PATENT OFFICE.

JOHN C. RICHMOND, OF HELPER, UTAH.

SELF-LEVELING TABLE.

1,153,828.

Specification of Letters Patent. Patented Sept. 14, 1915.

Application filed March 10, 1915. Serial No. 13,389.

To all whom it may concern:

Be it known that I, JOHN C. RICHMOND, a citizen of the United States, residing at Helper, in the county of Carbon and State 5 of Utah, have invented certain new and useful Improvements in Self-Leveling Tables; and I do hereby declare the following to be a full, clear, and exact description of the invention, such as will enable others skilled in 10 the art to which it appertains to make and use the same.

This invention relates to new and useful improvements in self-leveling tables, and has for its principal object to provide a device 15 which is particularly adapted for use on ships and the like.

Another object of the invention is to provide a table which is automatically balanced so that regardless of the rolling of the ship 20 the top of the table will remain level.

A further object of the invention is to provide a table having a plurality of auxiliary weights which are arranged to provide a means for leveling the table in event the ship 25 on which it is used, tilts to one side or the other and remains in that position for any marked length of time.

With these and other objects in view, the invention consists in the novel combination 30 and arrangement of parts which will be fully set forth in the following specification and accompanying drawings, in which,

Figure 1 is a view of a self-leveling table constructed in accordance with this invention 35 showing portions thereof broken away to more clearly illustrate the details of construction, and Fig. 2 is a sectional view taken on line 2—2 of Fig. 1 looking in the direction of the arrows.

40 Referring now to the drawings by characters of reference, the numeral 1 designates the legs of the device which, in the present embodiment of the invention, are three in number and are secured at their upper ends 45 to the ring 2. It is to be understood that these legs may be formed integral with the ring 2 if so desired. Formed centrally of the ring is an inclined face 3 which is provided with an annular groove 4 which forms 50 a ball race in which the ball bearings supporting the device are operably mounted. A suitable ball-retaining ring 5 is provided and is arranged to be screwed or otherwise secured to the upper surface of the ring 2 so 55 that its inner edge partially overlies the ball

race and prevents the balls contained therein from being displaced.

The main body portion of the table, designated generally by the numeral 6, comprises the top 7 which is screwed or otherwise secured to the semi-spherical member 8 which is located centrally of the body and is of such a diameter as to fit within the ring 2 and bear against the balls 9 mounted in the ball race. Formed centrally and depending from 60 the semi-spherical body 8 is a suitable collar 10 having formed therein the internal screw threads 11, the use of which will appear as the description proceeds. Extending outwardly at ninety degrees from each other 65 are the arms 12 which are formed integral with the collar 10, and these arms are for the support of the auxiliary weights which will be more fully hereinafter described.

The main weight, designated generally by 75 the numeral 13, comprises the spherical body 14 which is formed with the threaded stem 15, which stem is arranged to be threaded into the threaded opening 11 of the collar 10, and thereby support the weight 14 80 in a suspended position beneath the table. In order that the table may be leveled in case the vessel tilts and remains so for any period, the weights designated generally by 85 the numeral 16 are provided, and comprise the spherical body 17 having formed thereon the sleeves 18 which are provided with suitable set screws 19. These sleeves 18 are 90 slidable on the arms 12, and it will be apparent that as they are shifted toward the ends of the arms, the greater will be the pull on the table to tilt the same in that direction.

It will be apparent from the foregoing 95 that in use the legs 1 are secured to the floor or deck of a boat in any suitable manner, and it will be apparent that the weight 13 will cause the table to remain level regardless of the rolling of the boat. In event it is necessary to provide an auxiliary means 100 for assisting in balancing the table, the weights 17 are placed on the arms and may be shifted to any desired position thereby enabling the user to assist the weight 13 in holding the table level to prevent the contents thereof from being accidentally upset.

While in the foregoing there has been shown and described the preferred embodiment of this invention, it is to be understood 105 that such changes may be made in the com- 110

bination and arrangement of parts as will fall within the spirit and scope of the invention as claimed.

What is claimed is:

- 5 1. A table of the character described comprising a ring having a ball race formed therein, legs supporting the ring, a semi-spherical member extending through the ring and resting upon the balls, a table carried by the upper face of said semi-spherical member, a circular interiorly screw threaded collar secured centrally in bottom walls of said semi-spherical member, a plurality of arms radiating from said collar in opposite directions, means slidably adjustable upon said arms for changing the position of the semi-spherical member, a weight having a screw threaded projection formed thereon adapted to engage the internal screw threads of the collar of the semi-spherical member for holding the table level.
- 10 2. A self-leveling table of the character described comprising a circular ring, legs
- 15
- 20

Copies of this patent may be obtained for five cents each, by addressing the "Commissioner of Patents, Washington, D. C."

supporting the ring, said ring being formed with a ball race, balls in the ball race, a semi-spherical member resting on the balls and extending part way through the ring, a table secured across the top surface of the semi-spherical member, a collar secured centrally to the bottom wall of the semi-spherical member and extending therefrom, a plurality of arms radiating from said collar in opposite directions, weights provided in the collars and slidably mounted on the arms and means for adjusting the weights upon said arms, an enlarged weight provided with a screw threaded projection adapted to be secured to the collar of the semi-spherical member for holding the table level.

In testimony whereof I affix my signature in presence of two witnesses.

JOHN C. RICHMOND.
